WINDOW SUPPORT AND GUIDING MEANS

Alfred H. Haberstump, Detroit, Mich., assignor to
The Murray Corporation of America, a corpora-
tion of Delaware

Application April 22, 1935, Serial No. 17,560

6 Claims. (Cl. 296—48)

This invention is a continuation in part of my co-pending application, Serial Number 693,535, filed October 14, 1933 and pertains to window supporting means and particularly to the supporting and guiding means for a window mounted in the door of a cabriolet type of body.

It has been the practice heretofore in providing windows for doors of the cabriolet type, that is to say, for doors ending at the belt line of the body, to provide a frame about the glass having extensions at the lower side edges which act as guides and supports when the window is in raised position. The guides operate in channels at the edges of the doors and are provided with friction reducing means, such as felt, balls, wheels, spring pressed plates and the like, which not only permit the free operation of the frame, but, being biased in opposite directions, prevent the lateral and longitudinal tilting movement of the window. In practicing my present invention, I made possible such a support for a window in a door of the above mentioned type which is disposed in the vicinity of the wheel housing. In view of the presence of the wheel housing in the body, the rear lower portion of the door must be cut away and for this reason the downwardly extending leg on the rear portion of the window can no longer operate at the rear door edge. To overcome this difficulty, I have off-set the guide at the rear edge of the window inwardly thereof sufficiently to clear the cut-away portion of the door. Matable elements, in the nature of tracks or similar sliding related members, may be employed, one secured to the window and one to the door, inwardly of the cut-away portion, to guide and support the rear edge of the window in all of its positions.

The portion of the element to be secured to the window is braced by a casting which is fixed to the lower edge of the window frame. The casting is provided with a projection which extends upwardly over the rear edge of the frame to brace and strengthen the corner of the window. The track member is thereby rigidly secured to the window in a manner to eliminate any interference with the rail at the cut-away portion of the door. The guiding member engageable by the element on the window, is rigidly mounted within the well of the door and rigidly retains the window against tilting in any of its positions. Suitable rollers and other friction resisting means, which may be spring biased to provide proper rigidity to the window to prevent it from tilting, may be employed on either one, or both of the

elements, to eliminate friction and at the same time rigidly support the window for movement.

Accordingly, the main objects of my invention are: to provide a guiding and supporting element on the window of a door inwardly from the edge thereof and braced by a casting which extends between the window edge and the element; to provide a fixed guide inwardly of the rear door edge and parallel to the guiding channel at the front edge of the door, of a cross section to be engaged by an element on the window to support and guide the window in all of its positions; to provide rollers between the guiding elements on the door and window to assure an ease of travel to the window and a rigid support in all of its positions; to provide a casting which extends between the supporting elements on the window and the window frame and which projects over the rear edge of the frame to provide further strength to the assembly; and, in general, to provide a support for a window at the cut-away portion of the door which is simple in construction, economical of manufacture and positive in operation.

Other objects and features of novelty of my invention will be either specifically pointed out or will become apparent when referring, for a better understanding of my invention, to the following description taken in conjunction with the accompanying drawings, wherein:

Figure 1 is a broken view, partly in section and partly in elevation, of a door and window embodying features of my invention;

Fig. 2 is an enlarged broken view, partly in section and partly in elevation, of a portion of the window and its support illustrated in Fig. 1;

Fig. 3 is an enlarged sectional view of the structure illustrated in Fig. 1 taken on the line 3—3 thereof;

Fig. 4 is a sectional view of the structure illustrated in Fig. 2, taken on the line 4—4 thereof;

Fig. 5 is an enlarged, broken sectional view of a portion of the door illustrated in Fig. 1, showing the opposite side thereof from the portions illustrated in Fig. 2.

I have illustrated in Fig. 1, a door 10 for a cabriolet type of body 11 to be employed adjacent to the wheel housing of the body in such manner as to require the lower right hand corner of the door to be cut away at 12 to mate with the wheel housing portion of the body. A window glass 13 is disposed between the inner and outer panels of the door in the conventional manner, having a frame 14 thereabout for providing a support for the glass and engagement for an actuating mechanism 15 by which the window is moved to a pre-

determined position through the operation of a handle 16. Arms 17 on the regulator 15 are secured to a plate 18 attached to the lower portion of the frame 14. The plate 18 has slots 19 therein in which headed pin 21 on the ends of the arms 17, slide. The slots 19 are enlarged at 22 at their adjacent ends to permit the heads of the pin 21 to project therethrough for attaching and securing the frame 14 to the arms 17.

10 The front edge 23 of the window is extended at 24 below the frame 14 to provide a support for the front edge of the window when the window is in raised position. This is illustrated more clearly in Fig. 5 wherein the extension 24 operates in a channel 25 provided on the front rail of the door. The extending portion 24 is provided with pairs of rollers 26 of conventional form which are spring biased in opposite directions outwardly, to provide a resistance to a lateral tilting movement of the window when the extension 24 is supported in the channel 25. A bracing element 27 may be employed between the extension 24 and the plate 18 to provide rigidity to the assembly in the plane of the window.

25 The rear edge of the window is supported in a new and novel manner to provide clearance for the operation of the window within the door relative to the cut-away portion 12 thereof. It will be readily appreciated that an extension 24 on the rear edge of the window would prevent the lowering of the window any appreciable amount in view of the interference with the cut-away portion 12 of the door. To provide adequate support for the window and have the window movable a desired amount within the door, I have utilized a guide element 31 which has mated therewith a slidable element 32 which is secured to the window frame 14.

30 The element 32, herein illustrated, is of channel shape, engageable with the element 31 which is of T-shape. This engagement is effected through rollers 33 which may be spring pressed to retain the elements in mated, slidable relation against a tilting movement. The element 32 is secured to the frame 14 by a casting 34 of triangular shape, one branch 35 of which is secured to the elements 32 by screws 36. Another branch 37 of the casting 34 is secured to the frame 18 by suitable means, herein illustrated as by rivets 38. The bracket 34 has an extending flange 39 which projects upwardly over the rear end of the frame 14 as illustrated more clearly in Fig. 2. The rear flange of the frame 14 has screws 41 extending therethrough for securing the frame 55 to the casting. The casting may be more rigidly secured to the frame 14 by a screw 42 which extends completely across the frame 18 as illustrated in Figs. 2 and 5. When the frame element 18 is of sufficient strength this screw 42 may be omitted.

60 The casting 34 is similar to that illustrated and described in the above mentioned co-pending application and is employed for the same purpose, that of rigidly securing a guide element to the window frame inwardly from the edge thereof. In the co-pending application, a channel is provided which is of a depth equal to the distance of the guiding element from the edge of the window for the purpose of encompassing 65 said edge and providing engaging means for said guiding element. In the present construction, the channel of extended depth is eliminated by employing a guide element interjacent the edges of the window, which is rigidly secured to the 70 door, and which operates in a manner somewhat

similar to the operation of the guide element illustrated and described in the patent to Otto F. Graebner, Number 1,939,976, issued December 19, 1933, and assigned to the assignee of the present invention.

75 The casting 34 materially strengthens the corner of the frame and rigidly retains the movable element 32 rigidly on the window 13. While I have shown specifically the element 31 as being of T-shape and the element 32 as being of channel shape carrying rollers 33 in contact with the element 31, it is to be understood that other elements of channel or other shape well known in the art to be suitable may be substituted for the elements 31 and 32, illustrated, for guiding and supporting the window.

80 As will be evident from Fig. 1, the location of the elements 31 and 32 permit the window to be lowered completely into the well of the door without interference with the metal defining the cut-away portion 12. This is effected by having one element rigidly supported inwardly of the rear door edge and parallel to the channel 25 at the front edge of the door. The window is provided with an element engaging means which slides thereon in a path parallel to the channel 25. The window is rigidly retained against tilting movement in its plane as well as against a tilting movement laterally thereof through the engagement of the rollers 26 in the elements 24 30 on the front edge of the doors and through the engagement of the rollers 33 and the elements 31 disposed inwardly from the rear edge of the doors. The employment of the particular casting 34 is unique in providing rigidity to the window frame and supporting the elements 32 in rigid relation thereto so as to prevent a tilting movement or the flexing of the window due to the lack of rigidity of the elements 32 or the frame.

85 While I have described and illustrated but a single embodiment of my invention it will be apparent to those skilled in the art that various changes, additions, omissions and substitutions may be made therein, particularly in substituting well known elements similar to elements 31 and 32 45 for the guides in the rear portion of the door inwardly to the rear edge thereof, without departing from the spirit and scope of my invention, as set forth in the accompanying claims.

90 I claim as my invention:

1. A door for a vehicle body having a well therein, a window having a frame thereabout moveable downwardly and upwardly into and from said well, a guide on one edge of said frame extending below the window, a guide extending below the window inwardly from the opposite edge of said window, a casting interconnecting said guide and said frame, said casting having a projecting flange extending above the corner of said window, and means for securing said casting to the corner of said frame and said guide.

95 2. A door for a vehicle body having a well therein, a window having a frame thereabout moveable downwardly and upwardly into and from said well, a guide on one edge of said frame extending below the window, a guide extending below the window inwardly from the opposite edge of said window, a casting interconnecting said guide and said frame, said casting having a projecting flange extending above the corner of said window, means for securing said casting to the corner of said frame and said guide, and guide receiving elements one disposed at the edge of the door within the well and another disposed

within the well inwardly from the opposite edge of the door.

3. A window having a frame thereabout, a guide element disposed on said frame inwardly from the edge thereof, a casting secured to said frame and to said guide element, said casting having an extending portion which projects over the edge of the frame from which said guide is inwardly disposed.
- 10 4. A door for a vehicle body having a well therein, a window having a frame thereabout movable downwardly and upwardly into and from said well, a guide on one edge of said frame extending below the window, a guide extending below the window inwardly from the opposite edge of said window, a bracket interconnecting said guide and said frame, said bracket having a projecting flange extending above the corner of said window, means for securing said bracket to the corner of said frame and said guide, and guide receiving elements one disposed at the edge of the door within the well and another disposed within the well inwardly from the opposite edge of the door.
- 15 5. In an automobile window construction, a body formed with a well, a window sash movable into and out of the well, out of and into closed position and including a bottom rail and a hollow stile, and means located in the well between the side edges of the sash for guiding the sash in its movement, said means comprising a guide in the well and offset out of the path of the sash, a bracket secured to the sash and having a portion extending along the lower edge of the bottom rail, and an angular prong extending lengthwise into the hollow stile of the sash and secured thereto, the sash seating in the corner formed by the prong and said portion, and a carriage secured to the bracket and movable along the guide, the bracket forming a support and brace for the carriage substantially throughout the length thereof.
- 20 6. In an automobile window construction, a body formed with a well, a window sash movable into and out of the well, out of and into closed position and including a bottom rail and a hollow stile, and means located in the well between the side edges of the sash for guiding the sash in its movement, said means comprising a guide in the well and offset out of the path of the sash, a bracket secured to the sash and having a portion extending along the lower edge of the bottom rail, and an angular prong extending lengthwise into the hollow stile of the sash and secured thereto, the sash seating in the corner formed by the prong and said portion, and a carriage secured to the bracket and movable along the guide, the bracket forming a backing for the carriage at the upper and lower ends thereof, said bracket being triangular in general form with one side of the triangular formation extending along the bottom rail, another side of the triangular formation extending vertical, and the carriage being secured throughout its length to the vertical side, and the third side of the triangular formation inclining from the lower end of the carriage to the outer corner of the sash.
- 25 7. In an automobile window construction, a body formed with a well, a window sash movable into and out of the well, out of and into closed position and including a bottom rail and a hollow stile, and means located in the well between the side edges of the sash for guiding the sash in its movement, said means comprising a guide in the well and offset out of the path of the sash, a bracket secured to the sash and having a portion extending along the lower edge of the bottom rail,

ALFRED H. HABERSTUMP.
